UNITED STATES PATENT OFFICE.

JOHN CHESNEY, OF PAULSBORO, NEW JERSEY, ASSIGNOR TO THE E. I. DU PONT DE NEMOURS POWDER COMPANY, OF WILMINGTON, DELAWARE, A CORPORATION OF NEW JERSEY.

FOLDER FOR CLOSING THE ENDS OF PAPER SHELLS.

No. 905,844.

Specification of Letters Patent.

Patented Dec. 8, 1908.

Application filed February 24, 1908. Serial No. 417,462.

To all whom it may concern:

Be it known that I, JOHN CHESNEY, a citizen of the United States, residing at Paulsboro, county of Gloucester, and State of New Jersey, have invented a new and useful Improvement in Folders for Closing the Ends of Paper Shells, of which the following is a full, clear, and exact description, reference being had to the accompanying drawings, which form a part of this specification.

The invention relates to devices for folding or crimping the projecting ends of shells formed on the rotating mandrel of a shell machine for the purpose of closing the ends thereof.

The object of the invention is to so construct the folder that the sheet from which the shell is formed will be so folded that one or more series of folds will be tucked in beneath another series of folds in order to more securely close the end. Heretofore it has been old to attach to a wheel, secured to a rotating shaft, a rotating folder or crimper comprising a plurality of radially extending fingers, spaced apart, adapted in their rotation, and during the rotation of the mandrel and the formation of the shell, to successively engage the edge of the paper projecting beyond the mandrel and form a plurality of successively overlapping triangular shaped folds. This form of folder is extremely simple in construction and effective in operation, but the folding effected thereby is found to be more or less insecure, and the more specific object of the present invention is to modify the construction of the folder of the character above set forth, for the purpose of effecting the more certain and tight closure of the end of the shell. This object is effected by means of a folder or crimper embodying the essential features of the folder illustrated in the accompanying drawings, hereinafter described, in which—

Figures 1, 2, 3 and 4 each represent a side view of the folder in association with means for rotating the folder, the mandrel, the feed table, and the paper sheet forming the shell, the several views showing the operation of the folder upon the paper sheet from the beginning of the folding operation, illustrated in Fig. 1, to the end thereof, shown in Fig. 4. Fig. 5 represents a plan view of the folder, the means for directly rotating the mandrel and the feed table.

a represents the feed table upon which are placed the sheets of paper successively delivered to the rotating mandrel *b*, which is shown as turning in bearings *c* secured to the machine frame *d*. Also secured to the machine frame is a bearing *e* in which turns the gear wheel *f* to which is secured the folder. The gear wheel *f* and the mandrel *b* are each actuated to continuously rotate by means of connections from the main driving shaft, said connections not being shown nor described, as they form no part of the invention.

The folder or crimper consists of a plate *g* secured to and projecting beyond the periphery of the gear wheel *f*. The plate *g* is provided with two series of crimping fingers, the series *h* comprising seven fingers spaced apart and the series *i* comprising four fingers spaced apart, the two series of fingers being separated one from another by a substantially greater space than separates adjacent fingers of the same series. The fingers all project in a substantially radial direction from the shaft of the gear wheel *f* and are so located with respect to the mandrel that in their travel they successively pass close to and in front of the forward end of the mandrel.

In operation the mandrel and folder are rotated in the direction indicated by the arrows. The sheets of paper *j* on the table *a* are successively fed forward to the mandrel by means not shown, and are preferably held against the periphery of the mandrel during rotation by means of air suction applied to the interior of the mandrel, this suction being effective to so hold the paper by means of the perforations *b'* in the mandrel. The rotation of the mandrel and the rotation of the folder are so timed that, at a predetermined time after a sheet starts to be wound upon the mandrel, the first finger of the series of fingers *h* will engage the forward edge of the paper sheet projecting beyond the forward end of the mandrel and form the initial fold, as shown in Fig. 1. In the continued rotation of the mandrel and the folder, the remaining fingers of the series of fingers *h* will successively engage the edge of the paper sheet, thus bending it into a series of short, overlapping crimps or folds, as illustrated in Fig. 2. As the folder and mandrel continue to revolve, the remainder of the paper sheet

will be wound upon the mandrel, but during this operation, owing to the space between the series of fingers *h* and the series of fingers *i*, the folder will not act upon the paper. 5 The first finger of the series of fingers *i* reaches its operative position at about the time that the side edge of the paper reaches the mandrel, and this finger consequently acts upon the corner of the paper shell, causing it to be folded in upon the top of the series of folds formed by the fingers *h*, as shown in Fig. 3. Continued rotation of the mandrel and folder causes the remaining fingers of the series of fingers *i* to act upon the overhanging forward end of the shell to bend it into a series of short, overlapping crimps or folds that bury or confine the corner of the paper sheet last fed to the mandrel, as shown in Fig. 4. Thus the end of the shell is securely folded or crimped by means of two or more series of overlapping crimps or folds, while the corner of the sheet last fed to the mandrel is confined beneath the overlapping folds of the latter series, the effect being to 25 form what is practically a double or triple bottom, thus folding in the end of the shell so securely that there is no danger of its becoming accidentally opened in subsequent use. 30 Having now fully described my invention, what I claim and desire to protect by Letters Patent is:

1. A folder for crimping the ends of paper tubes, comprising a rotatable plate provided with two series of fingers projecting there-

from, one series being separated from the other series by a substantial space.

2. A folder for crimping the ends of paper tubes, comprising a rotatable plate provided with two series of fingers projecting therefrom, adjacent fingers of each series being spaced apart and the two series of fingers being separated by a space substantially wider than the space between adjacent fingers of the same series. 40

3. In a paper shell machine, the combination with a rotatable mandrel, of a rotatable shaft, a plate, carried by the shaft, provided with two series of fingers extending substantially radially of the shaft and adapted, in the revolution of the shaft to travel in front of, and in close proximity to, the forward end of the mandrel, the two series of fingers being separated by a substantial space. 45

4. In a paper shell machine, the combination with a rotatable mandrel, of a plurality of series of fingers and means to cause the same to pass successively in front of, and in close proximity to, the forward end of the mandrel, adjacent series of fingers being separated by a space substantially wider than the space between adjacent fingers of the same series. 50 55

In testimony of which invention, I have hereunto set my hand, at Paulsboro, on this 3rd day of Feby., 1908.

JOHN CHESNEY.
